UNITED STATES PATENT OFFICE.

ANDREW EPPLER, OF LYNN, MASSACHUSETTS, ASSIGNOR TO UNITED SHOE MANUFACTURING CORPORATION, OF PATERSON, NEW JERSEY, A CORPORATION OF NEW JERSEY.

SEWING MACHINE.

Application filed September 25, 1920. Serial No. 412,705.

In the manufacture of welted boots and shoes, it is customary to beat out the welt after the welt has been secured to the upper and insole in order to cause it to lie flat in substantially the plane of the insole. As the sidewise deflection of the welt in applying it to the toe portion of a shoe, particularly a pointed toe shoe, causes the welt to turn or curl up at the toe, this portion of the welt is usually provided with a series of cuts or slashes in its under surface to enable the outer edge thereof to stretch sufficiently during the beating out operation to bring it into the plane of the insole. To accomplish such slashing of the welt at the toe portion, it has been proposed to apply a welt slashing mechanism to the welt beating machine. Considerable difficulty, however, has been experienced in properly slashing the welt at this time, this difficulty being due mainly to the described turned up condition of the toe portion of the welt after it is applied to the shoe. Accordingly, it has been proposed to apply a manually controlled welt slashing mechanism to the welt sewing machine in such a manner that the welt may be slashed in advance of the stitch forming devices, the slashing of the welt at this time being advantageous in that the slashing knife operates on the welt while the welt is held substantially flat and the slashes enable the welt to be more easily laid about the toe of the shoe during the sewing operation. Such welt slashing mechanisms heretofore applied to welt sewing machines, however, have been dependent upon the operation of the welt guide of the machine or else the welt slashing knife of such mechanisms has been mounted in the welt guide. In welt shoe sewing machines in general use at the present time the movement of the welt guide is variable in extent and the welt guide is usually brought against the shoe by a relatively light spring so that a welt slashing mechanism cannot be associated with the present welt guide in the manner above described, without interfering materially with the operation of the welt guide. Also, the positioning of a welt slashing mechanism adjacent the sewing point would obviously interfere with the proper manipulation of the shoe by the operator.

Accordingly, one of the objects of the present invention is to provide a mechanism of the type above described adapted to be applied to a welt shoe sewing machine that overcomes

the disadvantages of the prior constructions. To this end, a feature of the present invention contemplates the provision in a welt shoe sewing machine of means under the control of the operator for operating on a welt at a distance in advance of the welt guide to facilitate the beating out of the welt. While this feature of the present invention in its preferred form contemplates the use of a welt slashing mechanism, it is to be understood that, except as defined in the claims, this feature as well as certain other features of the invention is not limited to a welt slashing mechanism as, obviously, it may include other mechanisms for operating on a welt in advance of the stitch forming devices to assist in the beating out operation. Preferably, the distance that the mechanism is spaced from the stitch forming devices corresponds substantially to the distance from the point on a shoe where the inseam stitches start usually the heel breast line to the toe portion of the shoe, so that when the shoe is initially presented to the machine its toe portion will extend past the operating instrumentalities of the mechanism. A gage is thus provided through which the shoe as it is fed to the sewing mechanism indicates to the operator when the slashing mechanism should be thrown into operation in order that the part operated on may register with the toe of the shoe. The operator may therefore readily start and end the operation of the mechanism to operate only on the portion of the welt that will register with and be laid about the toe portion of the shoe. Also, with such positioning of the mechanism it may be thrown into operation substantially at or shortly after the start of the sewing operation, and be thrown out of operation before the toe portion of the shoe is reached, so that the additional burden of throwing the mechanism into or out of operation is not placed upon the operator while sewing about the toe of the shoe, which is the most difficult part of the shoe to sew.

While in the present embodiment of the invention the means for throwing the mechanism into and out of operation is operable independently of the means for throwing the sewing machine into and out of operation, it will be apparent that the mechanism may be thrown into operation through suitable connection with the means for throwing the sewing machine into operation and may be

thrown out of operation either by the operator or automatically after a predetermined period of operation. Accordingly, the above described feature of the invention, 5 in its broader aspects, is not limited to a construction in which the means for controlling the operation of the mechanism is operated in the specific manner of that of the present embodiment of the invention, as it 10 may include a construction in which the mechanism is thrown into operation upon the operator throwing the sewing machine into operation.

Other features of the present invention 15 consist in certain constructions, arrangements and combinations of parts hereinafter described and claimed, the advantages of which will be obvious to those skilled in the art.

20 The several features of the invention will be clearly understood from the following description and accompanying drawings, in which:

25 Figure 1 is a front elevation of a portion of the head of a welt shoe sewing machine embodying the features in their preferred form; Fig. 2 is a detailed side elevation of the welt slashing mechanism of the machine; Fig. 3 is a sectional plan view of the lower portion 30 of the welt slashing mechanism which is shown as operating upon a welt; Fig. 4 is a vertical sectional view taken on the line 4—4 of Fig. 3; and Fig. 5 is a detailed side elevation of the slashing knife and its actuating 35 mechanism.

The welt shoe sewing machine illustrated in the drawings is provided with a curved hook needle 2, a looper 4, a thread arm 6, a channel guide 8, a welt guide 10, and a welt 40 guiding and measuring device comprising a guide roll 12. The channel guide 8 is actuated through connection with a lever 14 having a cam roll on its upper end that engages a cam 16 carried by the cam shaft of the machine, and the welt guiding and measuring device is mounted on a standard 18 forming a part of the frame of the machine. The parts above described and their associated mechanisms may be and preferably are the 45 same as the corresponding parts of the machine illustrated and described in applicant's Patent No. 1,108,560, dated August 25, 1914, to which reference may be had for a full and complete description of these and other 50 parts of the machine.

55 The welt slashing mechanism illustrated in the drawing is arranged adjacent the guide roll 12 and between the guide roll and the welt guide 10. This mechanism is provided with a continually reciprocating welt slashing knife 22 that comprises a straight blade formed on the inner end of a cylindrical bar 26. The knife bar 26 extends through and is guided by a boss 28 projecting from a bracket 60 secured on a fixed stud 32 projecting from

the machine frame, the bracket being provided with a split collar which is clamped by a bolt 34 to the stud 32. The slashing knife is reciprocated by a carrier 36, the knife bar 26 extending through bosses 38 which are formed on the carrier and arranged at opposite ends of the boss 28, and the knife bar being secured to the carrier by a set screw 40 threaded through an aperture in the outer boss 38. The carrier 36 is mounted to slide on a rod 42 that extends through and is secured by a set screw 44 to a boss 46 formed on the bracket 30, the carrier being provided with bosses 48 that are in sliding engagement with the ends of the rod 42. The carrier 36 is continually reciprocated to actuate the slashing knife by the cam actuated lever 14 that also actuates the channel guide. The connection between the carrier 36 and the lever 14 comprises a bell crank 50 fulcrumed on the upper end of the bracket 30. The free end of the lower arm of the bell crank 50 engages a notch 52 formed in the top of the carrier 36, and the other arm of the bell crank is connected by a ball and socket joint with the lower end of a link 54. The upper end of the link 54 is connected by a ball and socket joint with the actuating lever 14.

50 The illustrated mechanism is provided with a welt guiding device 56 for presenting the welt to the action of the reciprocating knife. This welt guiding device comprises a vertical bar 58 which is mounted on a bracket 60 secured to the standard 18. The upper end of the bar is provided with an overhanging head 62, the under surface of which extends at right angles to the inner face of the bar. The welt is guided between the head 62 and a block 64 secured to the bar which engage opposite sides of the welt. To 55 compensate for different thicknesses of welt the block 64 is vertically adjustably secured to the bar by means of bolts 66 that extend through slots in the block 64 and are screw threaded into apertures in the bar. The outer edge of the welt is guided by the inner face of the bar 58 and the inner or grooved edge of the welt is guided by an edge gage 68. This edge gage comprises a plate which is held in position by a screw 70 extending through a slot in a downwardly extending portion 72 of the plate, the screw being provided with collars 74 arranged at opposite sides of the plate. It will be apparent that by turning the screw 70 the edge gage 68 may be adjusted to compensate for welts of different widths.

60 The head 62 of the bar 58 is cut away at 76 to permit the knife to act on the welt, the knife being arranged at an angle to the plane of the welt and inclined rearwardly from the welt. A cutting block 78 against which the knife acts is mounted in a socket in the upper end of the bar 58. It will be apparent that the actuation of the knife across the welt to-

ward its outer edge and against the cutting block insures clean and uniform slashes being made, as there is no tendency for the welt to buckle or cramp as might be the case if the knife acted in the opposite direction, as has heretofore been customary in welt slashing mechanisms. It will also be apparent that by adjusting the knife circumferentially that the depth angle of the slashes may be varied as desired.

It is desirable that the slashes in the welt shall be made in the portion thereof which is laid about the toe of the shoe, while being omitted in the remaining portion of the welt. Accordingly, the welt guiding device 56 is adapted to be moved vertically by the operator to deflect the welt into and out of the path of the reciprocating slashing knife. To this end the bar 58 is mounted to slide vertically on the bracket 60, the bar and bracket being connected by a dovetail connection 80. The bar 58 is moved upwardly on the bracket 60 to deflect the welt into the path of the knife by means of a treadle 82 located at the front of the machine in position to be conveniently operated by the knee of the operator. The bar 58 is connected with the treadle 82 by a rod 84 having one end pivotally connected with the lower end of the bar and its other end pivotally connected with an arm 86 of a bell crank pivoted at 90 on the frame of the machine, the treadle 82 being mounted on the lower end of the arm 88 at the bell crank. This upward movement of the welt guiding device is limited by a stop screw 92 screw threaded through an aperture in the arm 86 of the bell crank engaging the machine frame. It will be apparent that by adjusting the screw 92 that the depth of the slashes made in the welt may be varied as desired. When the treadle 82 is released, as shown by dotted lines in Fig. 2, the welt guiding device 56 is moved downwardly to deflect the welt beneath the path of the slashing knife by a spring 94 coiled about the rod 84 and interposed between the arm 86 of the bell crank and the machine frame, this movement of the welt guiding device being limited by a stop collar 96 adjustably secured to the rod, engaging the machine frame.

In order that the operator may readily determine the proper points on the welt to start and end the slashing operation to slash only the portion of the welt that will be laid about the toe portion of the shoe, the welt slashing mechanism is spaced a slightly less distance from the sewing needle than the distance from the point on a small size shoe at which the inseam stitches start to the toe portion of the shoe so that when the shoe is initially presented to the stitch forming devices its toe portion will extend past the knife. With this arrangement, when the shoe has been fed by the machine during the sewing operation to a

position so that the inner end of its toe portion is opposite the slashing mechanism, the position of the shoe with relation to this mechanism indicates to the operator that the part of the welt which will register with the toe of the shoe is about to pass through the slashing mechanism and that by depressing the treadle 82 he may start the slashing operation on this portion of the welt. The treadle may be released by the operator after the required number of slashes in the welt has been made.

It will be apparent that such spacing of the welt slashing mechanism from the stitch forming devices also obviates any danger of the mechanism interfering with the proper manipulation of the shoe during the sewing operation.

While the features described above are well adapted for use in a welt shoe sewing machine, it is to be understood that, except as defined in the claims, certain features of the invention are not limited to use in a machine of this type as they are also adapted for use in other machines for operating upon welts.

The nature and scope of the present invention having been indicated and a machine embodying the several features of the invention in their preferred form having been specifically described, what is claimed as new is:

1. A welt shoe sewing machine having, in combination, stitch forming devices, a welt guide, and means in advance of the welt guide for slashing a welt comprising a reciprocating welt slashing knife and means operating independently of the welt guide for moving the welt into and out of the path of the knife to cause a portion of the welt to be slashed and the remaining portion of the welt to remain unslashed during the sewing operation.

2. A welt shoe sewing machine having, in combination, stitch forming devices, a welt guide and means for slashing a welt in advance of the stitch forming devices comprising a reciprocating welt slashing knife, and means operating independently of the welt guide movable in a plane transversely of the knife for moving the welt into and out of the path of the knife to cause a portion of the welt to be slashed and the remaining portion of the welt to remain unslashed during the sewing operation.

3. A welt shoe sewing machine having, in combination, stitch forming devices including a needle, and means for slashing the welt in advance of the stitch forming devices and spaced at a distance from the needle corresponding substantially to the distance from the point on a shoe where the inseam stitches start to the toe portion of the shoe.

4. A machine for operating upon a welt having, in combination, stitch forming mechanism, a main welt guide to guide the welt at the sewing point, a reciprocating welt slashing knife, a second welt guide for normally guiding the welt beneath the slashing knife,

- and means for raising said second welt guide to bring the welt into the path of the slashing knife.
5. A welt shoe sewing machine having, in combination, stitch forming devices, a welt guide, a roll for guiding the welt in advance of the welt guide, a reciprocating welt slashing knife interposed between the welt guide and the guide roll, and means for deflecting the welt into and out of the path of the slashing knife.
6. A machine for operating upon a welt having, in combination, a pair of spaced welt guiding devices, a reciprocating welt slashing knife interposed between said devices, and means for deflecting the welt into and out of the path of the slashing knife.
7. A welt shoe sewing machine having, in combination, stitch forming devices, a channel guide, means comprising a cam actuated lever for operating the channel guide, means comprising a welt slashing knife for slashing the welt in advance of the stitch forming devices, and connections between the cam actuated lever and the slashing knife for actuating the knife.
8. A machine for operating upon a welt having, in combination, means for guiding a welt, and means comprising a knife acting to cut across the welt toward and through its outer edge for making slashes in the welt.
9. A machine for operating upon a welt having, in combination, means for guiding a welt, and means comprising a knife acting to cut across the welt toward and through its outer edge for making slashes in the welt, and a cutting block to cooperate with the knife edge.
10. A machine for operating upon a welt having, in combination, means for guiding a welt, and means comprising a knife acting to cut across the welt toward and through its outer edge for making slashes in the welt, and means for relatively moving the welt and the slashing knife into and out of effective operative position.
11. A machine for operating upon a welt having, in combination, a cutting block, means for guiding the welt across the cutting block, a reciprocating welt slashing knife to slash the welt as it is fed across the cutting block, and means comprising a carrier for the cutting block and said guiding means for moving the welt into and out of the path of the knife.
12. A machine for operating upon a welt having, in combination, means for guiding a welt, and means comprising a knife acting to cut across the welt toward and through its outer edge and inclined to the plane of the welt for making slashes in the welt.
13. A welt shoe sewing machine having, in combination, stitch forming devices, a welt guide at the sewing point, and means for slashing a welt in advance of the welt guide comprising a welt slashing knife acting to slash the welt independently of any action of the welt guide on the welt, and means for actuating the knife and for relatively moving the welt and knife transversely of the plane of the welt into and out of effective operative position.
14. A machine for operating upon a welt having, in combination, stitch forming mechanism, a welt guide to guide the welt at the sewing point, a welt slashing knife, means for actuating the knife, a second welt guide for normally guiding a welt beneath the slashing knife, and means for relatively moving the latter welt guide and knife transversely of the plane of the welt to move the welt and knife into and out of effective operative position.
15. A machine for operating upon a welt having, in combination, a pair of spaced welt guiding devices, a welt slashing knife interposed between said devices, and means for actuating the knife and for deflecting the welt into and out of the path of the knife.
16. A machine for operating upon welt having, in combination, a welt support, a welt slashing knife, and means for relatively moving the welt and knife to cause the knife to cut across the welt towards and through its outer edge.
17. A welt shoe sewing machine having, in combination, stitch forming devices, a welt guide located adjacent the stitch forming devices, and welt slashing means under the control of the operator located at a distance in advance of the welt guide to permit said means to operate independently of any action of the welt guide on the welt.
18. A welt shoe sewing machine having, in combination, stitch forming devices, a welt guide at the sewing point, and means under the control of the operator operating to slash a portion of the welt unsupported by the welt guide.
19. A welt sewing machine having, in combination, stitch forming devices, a welt guide at the sewing point, and welt treating means to facilitate a subsequent welt beating operation, said means being under the control of the operator and located at a distance in advance of the welt guide to permit said means to operate independently of any action of the welt guide on the welt.
20. A welt shoe sewing machine having, in combination, stitch forming devices, a welt guide adjacent the stitch forming devices, and means under the control of the operator for slashing the welt comprising an auxiliary guide for the welt located at a distance in advance of said welt guide, and a welt slashing knife to act on the welt as it passes through said auxiliary guide.
21. A welt shoe sewing machine having, in combination, stitch forming devices, a welt guide adjacent to the stitch forming devices,

- and means under the control of the operator for operating on the welt during the sewing to facilitate a subsequent welt beating operation, said means being located at a distance of the shoe to facilitate a subsequent welt beating operation while another portion of the welt of a length equal to the length of the portion operated upon and spaced therefrom is being sewed. 20
- 5 22. A welt shoe sewing machine having, in combination, stitch forming devices, and means under the control of the operator for making a plurality of slashes in the portion of the welt that is to be laid about the toe of the shoe while another portion of the welt of a length equal to the length of the slashed portion and spaced therefrom is being sewed. 25
- 10 22. A welt shoe sewing machine having, in combination, stitch forming devices, and means capable of being thrown into and out of operation during the operation of the machine for performing an operation on the portion of the welt that is to be laid about the toe
- 15
